SHOE SEWING MACHINE

Fred Ashworth, Wenham, and Carl F. Whitaker,
Beverly, Mass., assignors to United Shoe Ma-
chinery Corporation, Borough of Flemington,
N. J., a corporation of New Jersey

Application March 22, 1939, Serial No. 263,455

50 Claims. (CL. 112—38)

The present invention relates to shoe sewing machines, and is herein illustrated as embodied in a high speed lock-stitch sewing machine of the hook needle type adapted to sew the outsole to the welt and upper of a welted shoe, and provided with a take-up at one side of the work and a rotary loop taker for passing loops of needle thread over a locking thread supply case at the other side of the work.

It is an object of the present invention to provide a hook needle lockstitch sewing machine which will operate effectively at speeds higher than those in common use without the difficulties ordinarily inherent with present commercial sewing machines of the type referred to when the sewing speed is increased beyond the usual rate.

It is common practice in designing a lockstitch sewing machine to arrange the take-up actuating mechanism so that no substantial tension will be imparted to the thread in each sewing cycle except when a stitch is being set, thereby avoiding the possibility of crushing or abrading the strands of thread while moving at high speeds. At the time the stitch is being set, the tension is of necessity heavy, but since there is little, or no, movement of the thread over the thread handling devices, no injury to the thread occurs. To keep the thread free from substantial tension at other times while the thread is moving rapidly over the stitch forming devices, the take-up is actuated after each stitch is set to provide slack while the thread is being drawn through the work by the other stitch forming devices, and to take up thread only after each needle loop is freed from the loop taker. However, when a sewing machine is operated in this manner, difficulty may be encountered from irregular movements in the thread due to lack of proper thread control. When the thread does not move uniformly in forming a stitch, it may become looped about a projecting part or escape from accurate control of one or more of the stitch forming devices, causing an imperfect stitch or thread breakage. At lower sewing speeds, in earlier developed machines of this type, difficulty from this cause is not present. When the speed of sewing is so increased that the frequency and extent of interruption from this cause renders the total average time for sewing a shoe no shorter than required when sewing at speeds now in common use, additional speed no longer increases the productivity of the machine.

Heretofore, attempts have been made to take

out the slack in the needle thread while the needle loop is engaging the loop taker so that better control on the thread may be obtained. To take the slack out of the needle thread just before the loop is free of the loop taker, and yet to permit slack thread at the take-up side of the work while the needle loop is being carried about the thread case, it is necessary to actuate the take-up quickly with precision and then to cause a brief dwell in the take-up movement until the needle loop is free of the loop taker. Thus far, it has been found impractical to design a simple take-up actuating mechanism which will operate in this way at high speeds and with the required precision since the time between the points in each sewing cycle where the needle loop is fully extended about the thread case and where the needle loop is free of the loop taker in a high speed machine is too short.

20 A more specific object of the invention is to provide a hook needle lockstitch sewing machine which will operate in such a way that the needle thread is subjected to little or no tension during each sewing cycle, except when a stitch is being set and which has its stitch forming devices arranged to cause the thread to move in a manner more nearly uniform than heretofore.

25 A further object of the invention is to provide a high speed lockstitch sewing machine in which the successive positions of the thread will be kept uniform during each stitch forming cycle, and particularly in that part of the cycle where the needle loop is being freed from the loop taker. Further and more general objects are to 30 improve the construction and mode of operation of a sewing machine in order that it may be manufactured with less expense and maintained in operating condition with the exercise of less skill and ability than heretofore.

35 40 With these and other objects in view, an important feature of the present invention contemplates the provision in a high speed lock-stitch sewing machine having a hook needle, a rotary loop taker for passing loops of needle thread over a locking thread case and a take-up acting to provide slack in the needle thread as each loop is being carried about the locking thread case, of means for preventing with certainty a slack condition in the needle loop as 45 each loop is passing from the position of maximum extension about the thread case to a position where it is free to be drawn down by the take-up. This feature of the invention is embodied in the use of a yielding needle thread controller having such a range of movement that it

will permit the needle loop to be carried about the thread case while the needle thread at the take-up side of the work remains slack, but will hold yieldingly a sufficient supply of thread to permit the take-up to begin its taking up stroke before the needle loop is free from the loop taker without causing a destructible tension to be imparted to the thread after the slack is taken up by the take-up. In the illustrated form of this feature, the force exerted by the controller during its normal movement is extremely light, and that imparted when actuated beyond its normal movement is relatively heavy, approaching in intensity that required to set a stitch, so that the tendency is for the controller to remain at a position spaced from both limits of its yielding movement when the take-up engages the thread. Thus, there always remains a small amount of thread to be given up by the controller in case of unavoidable irregularity in the movements of the take-up and loop taker just before the needle loop is freed from the loop taker. By providing a controller of this type, it is possible to so time the movements of the take-up and the loop taker that the needle loop will be free of the loop taker invariably at the same angular position of the loop taker in each sewing cycle. Accurate control of the needle loop, therefore, is maintained while on the loop taker without exerting substantial tension on the thread even when the machine is operated at speeds above normal.

In order to prevent the needle thread controller from being drawn to the limit of its yielding movement, due to the needle loops reaching positions of maximum extension at slightly different times relatively to the rotation of the loop taker, according to a further feature of the present invention, a frictional tension is provided between the take-up and the work to prevent slack in the needle loop as the loop taker is carrying the loop about the thread case. The frictional tension is provided between the take-up and the work to prevent slack in the needle loop as the loop taker is carrying the loop about the thread case. The frictional tension, while exerting a relatively light drag on the thread, prevents the thread from moving in an erratic manner, when work of different thicknesses or qualities is being operated upon, so as to prevent the needle loop from being extended to a size greater than required to encircle the thread case where insufficient resistance from movement of the threads is exerted by the work. If the needle loop is extended beyond the point where it will pass about the thread case, it necessarily will result in slack thread if only for an instant so that by providing means separate from the work for causing the needle loop to reach a position of maximum extension, invariably at the same angular position of the loop taker, slack thread in the needle loop itself is avoided at any time while the loop is engaged by the loop taker.

Other features of the invention consist in novel and improved needle thread measuring mechanism arranged to cause an automatic variation in the depth to which the inter-locking threads of a stitch are set in the work, novel and improved presser-foot actuating and locking mechanism; an improved work feeding mechanism, novel and improved looper and loop spreader supporting and actuating mechanisms and other devices, combinations and arrangements of parts herein-after described and claimed, the advantages of which can be readily understood by one skilled in the art from the following description, taken in

connection with the accompanying drawings illustrating one embodiment of the invention.

In the drawings Fig. 1 is a view in elevation, looking from the right hand side of a machine embodying the present invention; Fig. 2 is a view in front elevation of the upper part of the machine; Fig. 3 is a front view on an enlarged scale, partly broken away and in section of a portion of the machine; Fig. 4 is a sectional detail view of the take-up roll and adjacent parts; Fig. 5 is a sectional view of an edge gage adjustment detail, taken along the line 5—5 of Fig. 3; Fig. 6 is a view in front elevation of the machine with certain parts removed and a portion of the driving gear train for the take-up shown in section; Fig. 7 is a sectional view of a portion of the machine, looking from the right side illustrating the presser-foot mechanism with the presser-foot in raised position; Fig. 8 is a view in right side elevation, partly in section, of a portion of the machine with the presser-foot raised; Fig. 9 is a similar view of the machine illustrating the presser-foot in lowered or clamping position; Fig. 10 is a side view, partly in section, of a portion of the machine looking from the left; Fig. 11 is a view in rear elevation of a part of the machine; Fig. 12 is a view on an enlarged scale and in section of a portion of the machine including the take-up with the take-up cover open; Fig. 13 is a view of the driving gear train and housing for the take-up actuating mechanism; Fig. 14 is a detail view illustrating the devices for adjusting the mesh of the gears in said driving gear train; Fig. 15 is a detail view of an off-center variable speed driving connection for the take-up; Fig. 16 is a plan view, partly in section of the edge gage and the fudge knife adjusting devices; Fig. 17 is a sectional detail view, taken along the line 17—17 of Fig. 18 illustrating the needle and awl supporting parts; Fig. 18 is a view of the same parts taken in section along the line 18—18 of Fig. 17; Fig. 19 is another sectional view of the same parts taken along the line 19—19 of Fig. 17; Fig. 20 is a perspective view of a sleeve comprising a part of the awl adjusting devices; Fig. 21 is a detail view in side elevation of the feed carriage and needle oiling device; Fig. 22 is a plan view of the feed carriage and actuating mechanism therefor; Fig. 23 is a side view of the presser-foot and actuating mechanisms therefor; Fig. 24 is a sectional view, taken along the line 24—24 of Fig. 23; Fig. 25 is a sectional view of the presser-foot lock taken along the line 25—25 of Fig. 23; Fig. 26 is a plan view, partly broken away and in section of a portion of the presser-foot and needle thread pull-off mechanism; Fig. 27 is a detail view of a portion of the presser-foot mechanism shown partly in section while the presser-foot engages the work. Fig. 28 is a similar view of the same parts indicating the positions of the parts at the end of a seam with the presser-foot raised from the work; Fig. 29 is a sectional view, taken along the line 29—29 of Fig. 23; Fig. 30 is a somewhat diagrammatic view, illustrating the usual method of locating the interlocking portions of locking and needle thread in the work as the work varies in thickness; Fig. 31 is a similar view indicating the manner of locating the interlocking portions of locking and needle thread when the work varies in thickness in the present machine; Fig. 32 is a detail view, partly broken away of the thread finger and a frictional device for aiding in control of the thread; illustrating the positions of the parts while the needle loop is being carried about the thread case; Fig. 33 is a

view of the same parts illustrating their positions while the needle is being looped; Fig. 34 is a sectional view, taken along the line 34—34 of Fig. 32; Fig. 35 is a further detail view of the frictional devices illustrated in Fig. 32; Fig. 36 is a sectional view taken along the line 36—36 of Fig. 35; Fig. 37 is a plan view of the shaft for supporting the needle thread pull-off and lock actuating mechanism together with the arrangement of the looper indicating the position of the looper before the thread is engaged by the thread finger; Fig. 38 is a detail view of some of the looper actuating parts showing their positions while the loop of thread is being laid in the barb of the needle; Fig. 39 is a similar view of the same parts indicating the path of the looper; Fig. 40 is a view in side elevation of a portion of the machine including the thread lifter and its actuating mechanism; Fig. 41 is a view of the same parts in plan; Fig. 42 is a detail view illustrating the method of handling the thread as a needle loop is being carried about the thread case; Fig. 43 is a similar view illustrating the positions of the same parts shown in Fig. 42 with the needle loop opened to a maximum extension about the thread case; Fig. 44 is a left hand side view of the shuttle and thread case in the positions illustrated in Fig. 43; Fig. 45 is a view similar to Fig. 43 illustrating the needle loop after being freed from the thread case and shuttle; Fig. 46 is a detail side view on an enlarged scale of the needle thread controller indicated in Figs. 42, 43 and 45; and Fig. 47 is a front view of the controller and its supporting means.

The machine illustrated in the drawings is of the type disclosed in prior U. S. Letters Patent of Ashworth Nos. 1,169,909 of February 1, 1916, 1,824,063 of September 22, 1931, and 2,015,654 of October 1, 1935. The machine is equipped with a curved hooked needle 2, a needle guide 3, a curved awl 4, a shuttle or loop taker 6, a thread case 8 mounted within the shuttle, a looper 10, a thread finger 12, a loop lifter and spreader 14, a work support 16, a presser-foot 18, and a rotary take-up, all similar, except as hereinafter pointed out, to those of the Ashworth patents. A driving and stopping mechanism is also provided for bringing the machine to rest with the work free to be removed from the machine.

The take-up, as shown in Figs. 3 and 12, includes an arm 20 secured to a rotating shaft 22 and is provided with a roll 24 so actuated as to draw down each needle loop after being freed from the shuttle into the work, set the stitch and give up thread at the times required by the other stitch forming devices. In order to avoid unnecessary strain on the thread, no substantial tension is imparted to the thread by the take-up except when the stitch is being set. At other times, and particularly while the needle loop is being drawn through the work and carried over the thread case, as indicated in Fig. 42, there is a substantial amount of slack thread between the take-up and the work or the take-up imparts only sufficient tension to the thread to cause it to be drawn through the work (Fig. 45).

The work is fed in the illustrated machine by the movement of the work support and presser-foot while clamping the work, as in the machine of Patent No. 1,824,063, and during the engagement of the presser-foot with the work a measured amount of needle thread is pulled off from the supply, the thread after measurement, being locked against further movement towards or

away from the supply until after each stitch is set by the take-up.

The shuttle and thread case are similar to those disclosed in the U. S. Letters Patent of 5 Minett, No. 2,208,999, dated July 23, 1940, in which the thread case is provided with a grooved thread guiding shoulder indicated at 26 (see Fig. 45) and other surfaces to assist in spreading the needle loop as it is carried about the thread case. The 10 shape of the thread case is such that as the shuttle carries the loop over the thread case the loop is opened by the surfaces of the thread case until a position of maximum extension in the loop is reached. Thereafter a further short angular 15 movement of the shuttle on the order of 10 degrees is required to free the needle loop with certainty. If the take-up is timed to exert a tension on the needle thread during this short angular movement of the shuttle, the loop may 20 become caught on the surfaces of the thread case due to uncontrollable irregular movements in the loop before being pulled tight or due to accumulations of wax or other matter on the shuttle or thread case. The shuttle of the present machine is rotated three revolutions for each 25 single rotation of the take-up and, on account of the number of parts in, and weight of, the driving mechanisms for the shuttle and take-up, slight variations may occur in their relative positions at the time each needle loop is being pulled 30 from the thread case by the take-up. For these reasons, it is usual in prior hooked needle sewing machines to so adjust the take-up that it will engage and tension the thread a substantial number 35 of degrees of rotation in the shuttle later than the position in which the needle loop ordinarily reaches maximum extension, thus avoiding any possibility of imparting undue strain on the thread by the take-up. Where the actuation of the take-up in pulling the needle loop 40 from the thread case is delayed in this way, the needle loop ordinarily is left slack at a critical time so that uniformity in movement of the needle loop after reaching a position of maximum 45 extension is not insured. Therefore, in spite of this precaution, non-uniform movements of the needle loop at this time may still result in irregularity of thread-handling, thread breakage or non-uniformity in the positions at which the inter-locking portions of threads in successive 50 stitches are set in the work.

To maintain the needle loop under light tension with certainty, without unduly straining the thread while the needle loop is passing from a position of maximum extension (Fig. 43) to a position where it is free to be drawn with certainty from the thread case and shuttle (Fig. 45) by the take-up, in the machine of the present invention, an extremely light weight spring actuated thread controller is employed having a relatively short range of movement and a suitable characteristic to insure a yielding effect in the needle thread with the application of any degree of tension on the thread short of that employed 55 to set the stitch.

The needle thread controller comprises a light angularly bent wire 28, as best shown in Figs. 46 and 47, secured in a block 30 rotatable on a stud 32 having one end threaded in the machine frame. The bent end of the wire 28 has a perforation 34 for guiding the thread and acts in a manner similar in some respects to an auxiliary take-up of conventional form, but the movement 60 of the controller is much shorter than with the usual auxiliary take-up so that only a very

small amount of thread is taken up when the wire is in released position (Fig. 42). The wire 28 engages the needle thread between two spaced guide rolls or trucks 36—38 and is actuated by a coiled spring 40 surrounding the stud 32 with its ends secured to a clamp collar 42 on the stud and to the block 30 respectively. To hold the wire 28 when fully released by the thread, an adjustable saddle 43 having projecting arms is loosely mounted on the stud 32. The saddle is formed with a suitable recess to receive the wire 28 and carries two set screws 44 and 46 threaded in the arms to engage the frame of the machine, thus permitting the position of the saddle to be adjusted. The saddle is so adjusted that the controller will take up only the thread left slack as a result of imperfections in the mechanical construction of the driving mechanisms for the take-up and the shuttle while each needle loop is being carried by the shuttle from a position of maximum extension to a position where it is free to be drawn down by the take-up, as indicated in Fig. 45.

To improve the operation of the controller further, the bent thread engaging end of the wire 28 is located centrally between the guide rolls 36—38 so that thread is drawn towards a right angle position from its natural straight line path. By this arrangement, a relatively light tension on the thread is sufficient to cause the controller to give up thread during the first part of its movement away from its fully released position, indicated in Fig. 42 and, as the thread approaches a straight line position between the rolls 36—38, a relatively heavy tension must be exerted to actuate the controller. Between the fully released position of Fig. 42 and a fully retracted position slightly beyond that indicated in Fig. 43, a rapidly and progressively increasing tension must be exerted to actuate the controller in a direction to give up thread. The force exerted by the spring 40 is so adjusted that the thread between the rolls 36—38 approaches or substantially reaches the straight line position only when a stitch is being set by the take-up. Thus, the controller is caused to assume an intermediate position (Fig. 43) between the released and fully retracted positions while the needle loop is being drawn from the thread case and shuttle by the take-up.

To control the needle thread more effectively while each needle loop is being formed and carried about the thread case, a light frictional tension device is provided between the take-up and the work so that sufficient tension will be applied to the thread between the time the needle is looped and drawn through the work and the time the needle loop reaches a position of maximum extension about the thread case. By maintaining a light tension on the thread between these times the needle loop is caused to reach a position of maximum extension invariably at the same angular position of the loop taker. Thereafter, as the interlocked needle loop and locking threads are being drawn down to the upper surface of the work by the take-up, the frictional tension on the thread prevents the thread from becoming loose along that portion operated upon by the thread pull-off and locking devices, to be described.

The frictional tension device includes a plate 48 (see Figs. 32 to 36 inclusive) formed with a cylindrical lug 50 rotatably mounted in a bracket arm 52 secured to the machine frame. The needle thread is carried past the plate 48 through 75

an opening in the right angle portion of a friction member 54 secured to an arm 66 pivotally mounted at 68 on the bracket 52. The arm 66 is slotted substantially throughout its length except for a U-shaped connecting portion (see Fig. 34), to receive a projecting portion of the friction member 54, and a thread guide roll 69 rotatable on the pivot 68, the member 54 being held in the slot of the arm 66 by a screw 70. 10 Between the pivot 68 and the screw 70, the arm 66 is perforated to receive a pivot pin 72 of an actuating connection. The pivot pin 72 is reduced along its central portion to receive that part of the friction member 54 which extends 15 within the slot in the arm 66, so as to lock the pin from axial movement while permitting rotation. The pin also fits within a notch formed in a thread retaining cage 73 surrounding the guide roll 69 to prevent rotation of the cage. Connected with the pin 72 at one side of the arm 66 is a block 74 having a threaded opening to receive an elongated screw 76 surrounding which is a compression spring 78.

The friction member 54 is actuated yielding 25 towards the plate 48 with two degrees of pressure by a connection with the thread finger 12 including a slide 80 having a perforated lug through which the screw 76 passes, positioned between the spring 78 and the head of the screw 76. 30 The slide 80 moves in a guideway formed in a two-armed bracket 81 and carries a pin 82 engaging a slot in the thread finger 12, the thread finger being in the form of a lever fulcrumed between the arms of bracket 81 by a pivot pin 84, and having a button shaped enlargement 85 at its lower end fitting between the arms of the bracket 81 to prevent side movement of the finger 12. By means of these connections the friction member 54 acts to compress the thread 35 yielding 40 against the plate 48 at all times and when the thread finger is moved rearwardly during the operation of laying the thread in the barb of the needle, as indicated in Fig. 33, the tension is increased to assist the looping operation.

To provide a measured amount of needle thread for each stitch, there is rotatably mounted between the take-up and the thread supply a pull-off comprising a curved and slotted 50 arm 86 (Fig. 12) secured to a sleeve 88 loosely surrounding a first shaft 90 rotatably mounted in the machine frame. Cooperating with the pull-off 86 is a thread measuring arm 92, the position of which is automatically adjusted by 55 the position of the presser-foot while in engagement with the work, the pull-off and measuring arm being actuated by mechanism similar to that in the machine of inventor's Patent No. 1,169,909 above referred to. The pull-off actuating mechanism includes an arm 94 (see Figs. 2 and 6) at one end of the sleeve 88, a link 96 connecting the arm 94 with one arm of a lever 98, another arm of which is connected with one end of a link 100, the other end of which surrounds a 60 crank 102 on one of the two sewing shafts 104 and 106. As in the machine of that patent, the thread measuring arm 92 is formed with a pair of thread guiding eyes between which the pull-off arm operates and is mounted at one end of 65 a second shaft 110 rotatably mounted in a bearing 112 bolted for convenience in assembly to the machine frame in alignment with the first shaft 90, a recess in the end of the shaft 110 supporting a bearing for one end of the shaft 90. The 70 connections for adjusting the position of the

measuring arm 92 include an arm 114 on the shaft 110 connected by means of a link 116 to the presser-foot actuating mechanism to be described more fully hereinafter.

The means for locking the thread, is best shown in Fig. 12 and comprises two thread locks, the front one of which operates on the thread between the pull-off and the work, and the rear one of which operates on the thread between the pull-off and the supply. The two locks are similar in construction and include thread guiding trucks 36 and 118 around which the thread passes on its way to the take-up from the supply. To clamp the thread on the surface of the truck 36 of the front thread lock, there is loosely mounted on the stud 32 a curved thread gripping shoe 120 having an inner surface fitting the surface of the truck 36 and an outer surface concentric with the inner surface. The shoe 120 also has a perforated extension through which the thread passes to prevent escape of the thread from the truck 36. To actuate the shoe 120 towards and from the truck 36, the outer surface of the shoe is engaged by a cam portion of an arm 122 secured to one end of the shaft 90. To the other end of the shaft 90 is fixed an arm 124 pivotally connected to the forward end of a horizontal rod 126 (see Figs. 10 and 37). The rod 126 is slidably supported in a sleeve 128 pivotally mounted at the lower end of a cam lever 130 fulcrumed at 132 above the rod 126 and actuated by a cam on the shaft 104. To actuate the rod 126 in a direction to force the arm 122 against the shoe 120 and close the thread lock, there is coiled about the rearward end of the rod 126 a spring 134 held under compression against the sleeve 128 by a nut 136. When the cam lever 130 is moved rearwardly the force of the spring is exerted to close the front lock and when the lever is actuated in the opposite direction, the sleeve 128 engages a collar 138 on the rod 126 and allows the front lock to open. The shape of the shoe 120 is such that when engaging the thread on the truck 36, the outer and inner surfaces of the shoe are substantially concentric with the axis of the truck. The force applied by the arm 122 on the shoe 120, therefore, is applied radially of the truck 36 in forcing the shoe against the truck, so that a direct clamping action on the thread results. The cam surface of the arm 122 is of the proper shape to engage the shoe at a point approaching the line connecting the axis of the truck and the center of the shaft 90 so that a constantly increasing force is applied by the shoe to the thread on the truck, as the lock is actuated, thus preventing the thread from slipping or forcing the shoe away from the truck.

The rear thread lock, including the truck 118, has a pivoted clamp shoe 140 and a cam arm 142 operated in substantially the same manner as in the front lock, the arm 142 being secured to one end of a sleeve 144 surrounding the sleeve 88 of the pull-off and having an arm 146 at the other end of the sleeve 144. The arm 146 has a pivotal connection with a rod 148 parallel to the rod 126 and slideable in a sleeve 150 pivotally mounted at the lower end of a cam actuated lever 152. The lever 152 operates through a spring 154 compressed between the sleeve and a nut 156. The rod 148 also carries a collar 158 to open the rear lock when the arm 152 is moved forwardly.

The construction and arrangement of the locks, pull-off and thread measuring arm in a

manner to be actuated from a central location including concentrically arranged shafts and sleeves renders the devices more effective and easily adjusted with relation to each other than where the devices are operated from widely separated mechanisms. Furthermore, when the same shaft is arranged to support the actuators for both front and rear thread locks, an arrangement of parallel operating rods may be provided in such relation as to be conveniently accessible for simultaneous lock releasing movement by means of a simple connection to the driving and stopping mechanism of the machine when the machine is brought to rest.

The driving and stopping mechanism is similar to that of prior Patents Nos. 1,169,909 above referred to and that of Ashworth 1,233,539 of July 17, 1917, being provided with high and low speed driving mechanisms, a continuously oscillated cam lever, indicated in Fig. 10 at 160, a locking pin or bolt 162, and a lock-bolt carrier 164 arranged to be connected with the cam lever 160 after the high speed driving mechanism is disconnected to render the low speed driving mechanism effective in bringing the machine to rest at a predetermined position. The position of the lock bolt is controlled through connections to a driving and stopping treadle rod 165, an arm 166 to which the rod 165 is pivoted, and a lever 167 connected to the lock bolt and arranged to be actuated by a cam surface on the arm 166. To prevent rotation of the sewing shafts of the machine past stopping position, the shaft 104 has a cam 168 cooperating with a lever 169 which lever is movable in a direction parallel to the shaft 104 towards and from engagement with the cam 168 and is arranged to be moved by the cam 168 radially away from the shaft 104 when brought into engagement with the cam to unlock and raise the presser-foot from the work. To open the thread locks and to perform other auxiliary operations, the lever 169 when actuated by the cam 168 moves against an arm 170 connected by a link 172 with an arm of a lever 174, the lower end of which carries two set screws 176 engaging the rearward ends of the rods 126 and 148. When the lever 174 is actuated by the cam 168, the set screws 176 force the rods 126, 148 forwardly compressing the springs 134 and 154 on the rods to open both locks so that the thread may be withdrawn freely with the work a suitable distance from the machine before severing the threads.

The thread locks are actuated by their respective cam levers alternately to release the thread, the rear lock being closed and the front lock opened to insure that the measured thread will be drawn from between the locks before each needle loop reaches a position of maximum extension about the thread case. The front lock remains open while each stitch is being set and is closed while the thread is under strain exerted by the take-up immediately after the take-up reaches its lowest stitch setting position, as in U. S. Letters Patent to Gouldbourn et al, No. 2,049,369 of July 28, 1936. Thereafter, both locks remain closed until the pull-off begins to act, at which time the rear lock is opened. In stopping the machine of the Gouldbourn patent, the take-up does not reach its stitch setting position. When the present machine is brought to rest, the take-up is already approximately at its lowermost stitch setting position so that, unless special means are provided, the locking thread held by

the bight of the last needle loop will be pulled down and the stitch drawn into the work.

To enable the operator to sever both threads of a seam at the same side of the work as with the use of the machine of U. S. Letters Patent to Ashworth No. 1,519,652, dated December 16, 1924, when the machine is brought to rest, it is necessary to allow the needle loop of the last stitch to remain outside the surface of the work. In order to cause the needle loop of the last stitch to remain outside the surface of the work when the take-up reaches its stitch setting position, the set screws 176 of the lock opening lever 174 and the position of the cam 168 on the shaft 104 are adjusted to cause both locks to be opened before the take-up reaches its lowermost position.

Referring to Figs. 21 and 22, the work support 16 is secured to a feed carriage having a pivotal mounting, the axis of which extends at an acute angle to the plane of the flat work engaging surface 178 of the work support. The work support is of U shape, the work engaging surface 178 of which is at the center of the U between the parallel arms. The arms of the support are clamped to parallel portions of the feed carriage indicated at 180, which carriage is constructed in two parts. The parts of the carriage are secured together and to an inclined pivotal mounting shaft 182 by bolts 183 passing through the parts. To clamp the work support to the carriage 180 and to provide convenient vertical adjustment for the work supporting surface 178, the parallel arms of the support are perforated to receive clamp screws 184 entering threaded openings in the carriage 180 and the carriage has passing loosely through its parallel portions eccentric headed bolts 185, the heads of which fit within slots formed in the work support. The work support has suitably located holes to provide access to slots in the heads of bolts 185 whereby the bolts may be rotated when the clamp screws 184 are loosened to raise and lower the work support.

The feed carriage pivot shaft 182 is rotatably mounted at its ends in bearings 181 and 186 (see Figs. 7 and 12) on the machine frame, both bearings being below the plane of the work engaging surface 178 of the work support at locations to provide ample space for the other operating mechanisms. The feed carriage 180 is reinforced between its pivotal mounting and the work by the formation of hooked portions on the carriage engaging thrust plates 188, the surfaces of which are at right angles to the pivotal axis of the carriage. The plates 188 are supported in seats formed on a bracket 189 bolted to the machine frame.

The presser-foot is secured to the forward end of a presser-foot lever 190 fulcrumed on a pin 192 supported in lugs extending from the right arm of the feed carriage. The pin 192 has a squared head engaging a slotted guideway in a plate 194 bolted to the bracket 189 to stiffen that portion of the carriage supporting the pin, the hooked portions of the carriage sliding along arcuate edges of the thrust plates 188 and the head of the pin 192 sliding in the slot of the plate 194 during feeding movements of the carriage.

The mechanism for imparting feeding movements to the feed carriage is similar to the mechanism for imparting the feeding movement to the awl in the prior Patent No. 1,169,909 and includes a rearwardly extending arm of the feed carriage pivotally connected to one member of a pair of toggle links 196 and 198 (see Fig. 22), the middle joint of which is connected by a link 200 to one

5 arm of a cam actuated bell crank lever 202. To change the length of stitch, the toggle link 198 is pivotally mounted on a yoke 204 rotatable in the machine frame on pivots approximately in line with the middle joint between the links 196 and 198. An adjustment of the yoke 204 about its pivots increases or decreases the angle formed by the links of the toggle, thus changing the feeding movements of the feed carriage. To adjust the yoke 204, it is provided with an arm 206 connected by a link 208 to one arm of a bell crank lever 210, the other arm of which is connected by a link 212 pivoted at 213 to a hand operated lever 214 (see Figs. 3 and 16).

To compensate for minor irregularities in the parts of the machine, and to adjust properly the position of the feed carriage without reference to the length of feeding movements, the pivotal connection between the toggle link 196 and the feed carriage comprises a pin 216 (see Fig. 21) passing through a forked end of the link 196 and an eccentric sleeve 218 adjustably clamped in the arm of the feed carriage between the forks of the link. To rotate the eccentric sleeve in the arm of the feed carriage, the sleeve is formed with a flange having spanner holes 220 into which a suitable tool may be inserted. Rotation of the sleeve causes relative positions of the feed carriage along the line of feed to be changed without affecting the length of the feeding movements.

Referring to Figs. 8, 9, 21 to 29 inclusive, the mechanism for actuating the presser-foot to clamp and release the work comprises an arm 222 pivoted on the presser-foot fulcrum pin 192 and connected with the presser-foot lever 190, a link 224 having universal joints at its ends connecting the arm 222 with a bell crank lever 226 fulcrumed on a pin 228 fixed in the machine frame, and a link 230 connecting the bell crank lever 226 and the lower end of a floating lever 232. To provide a pivot point at the lower end of the floating lever, the link 230 is forked (see Fig. 24) and embraces the slotted lower portions of the floating lever, a pivot pin 234 passing through the overlapping parts of the link and lever. To cause the presser-foot to be engaged yieldingly with the work, the central part of the pivot pin 234 within the slot of lever 232 passes through the forward end of a link 236, the rearward end of which is pivoted on a pin 238 mounted in a curved arm of a three-arm lever 240. The lever 240 is rotatably mounted on a fixed stud 242 and has connected to a downwardly extending arm the rear end of a relatively long tension spring 244, the forward end of which is connected to an arm 246 of a tension adjusting device. The spring 244 acts through the parts thus described to exert a yielding force in a direction to cause the presser-foot to engage and clamp the work. To adjust the force with which the presser-foot yieldingly engages the work, the arm 246 to which the presser-foot spring 244 is connected is pinned to the lower end of a vertical shaft 247 (Fig. 3) rotatable in the frame of the machine. Also on the shaft 247 there is made fast a worm gear 248 meshing with a worm 249 on a horizontal shaft 250 provided with an adjusting wheel 251. Rotation of the wheel through the worm 249 and gear 248 causes the arm 246 to be moved forwardly or rearwardly, increasing or decreasing the tension on the presser-foot spring 244.

To lock the presser-foot mechanism, the floating lever 232 is connected at a point midway between its ends with a locking device similar

to that disclosed in the patent to Gouldbourn et al. No. 2,054,078 of September 15, 1936. The construction of the locking device is illustrated in Fig. 25 and includes central and outer wedge members 252 located in a guideway in a block 253 bolted securely to the frame of the machine. Between the central wedge member and one of the outer wedge members there is a spacing piece 254 and between the central wedge member and the other of the outer wedge members is a series of steel rolls 255. A relatively fixed bar 256 projects into one end of the gap holding the rolls 255 and at the other end of the gap is a presser-foot locking finger 258 which, when actuated by mechanism hereinafter described, presses the rolls together, thus urging the locking members against the inner surfaces of the guideway and the outer surfaces of the spacing piece 254. The wedge members 252 are connected to the floating lever 232 by a pin 260 passing loosely through the members and lever so that, when the members are forced against the guideway, the pin 260 forms a fulcrum for the floating lever. When the fulcrum pin 260 is locked against movement by the locking device, oscillation of the floating lever 232 in one direction will cause the presser-foot to squeeze the work against the work support, and in the other direction to release the work from the grip of the presser-foot and work support. To oscillate the floating lever, the lever is connected at a point near its upper end with a cam actuated lever 262. The connection between the floating lever and the cam lever 262 is adjustable to cause different degrees of squeezing and releasing movements to be imparted to the presser-foot and comprises a link 264, the ends of which carry studs 266 releasably clamped within slots at the upper end of the lever 232 and the lower end of lever 262 respectively.

With certain types of work, it is desirable to permit the presser-foot to remain continuously in engagement with the work and to provide convenient means for permitting this manner of operation, the presser-foot lever 190 and the actuating arm 222 are connected together by means of a clamping screw 268 (see Fig. 21) passing through an upstanding arm of the presser-foot lever and into a threaded opening in a lug on the arm 222. Surrounding the screw 268 within an enlarged bore in the lug of the arm 222 is a coil spring 270 and, when the screw 268 is backed off, the spring 270 presses the presser-foot against the work with a light yielding action, the screw connecting the lever and arm only loosely. Such operation is desirable, for instance, in case a grooving knife is employed on the presser-foot. When the screw 268 is tightened, the presser-foot again will act in the usual way, the spring 270 being rendered inoperative and the lever 190 and arm 222 being rigidly connected.

The mechanism for actuating the presser-foot locking device includes the locking finger 258, which forms one arm of a lever 272 fulcrumed on a shaft 274 mounted in the block 253, a link 276 pivotally connected to one arm of the lever 272, and a cam actuated lever 278 fulcrumed on a cross shaft 280 in the machine frame for actuating the link 276.

To assist in releasing suctional effects along the gripping surfaces of the locking members 252, spacing piece 254 and the guideway in which they are mounted, when the locking device is unlocked, the gripping surfaces in the illustrated machine are provided with channels 282 forming

7 a number of projecting elements for gripping the cooperating surfaces of the guideway and wedge members. The channels 282 also provide clearance spaces between the gripping surfaces within which foreign material or loose particles scraped from the gripping surfaces may accumulate without interfering with the locking action.

To prevent engagement of the presser-foot and work support when no work is presented to the machine, the presser-foot lever 190 carries a stop plate 284 adjustably secured thereto by clamp screws 286 passing through slots in the plate 284. The lower surface of the plate 284, when the presser-foot is moved yieldingly towards the work support, strikes a forwardly projecting arm of a bracket 288 carrying the needle and awl supporting stud on the machine frame.

As in prior machines of the clamp feed type, the cam actuated lever 262 imparts a work squeezing and releasing movement to the presser-foot in proper timed relation to the feeding movements of the carriage 180, the squeezing movement occurring during feed and the releasing movement occurring during back feed of the carriage. To limit the pressure of the presser-foot on the work during its squeezing movement so as to avoid injury to the surface of the work, in the present machine the lever 262 is connected through a yielding element to a cam follower arm 289 (see Fig. 7). The lever 262 is fulcrumed on a shaft 290 and the arm 289 is provided with a pair of upstanding lugs between which a laterally projecting arm of the lever 262 enters. The laterally projecting arm of the lever 262 is formed with a recess within which is mounted a spring 292 acting between the bottom of the recess in the arm and the enlarged head of an adjustable set screw 294 mounted in one of the lugs on the cam arm 289. When the cam arm 289 is oscillated in a direction to force the presser-foot towards the work support and squeeze the work, it acts through the spring 292, but when the cam arm is oscillated in the opposite direction to raise the presser-foot from the work, the other lug of the arm engages the lever 262, rendering the spring 292 inoperative to hold the presser-foot against the work.

The connections between the driving and stopping mechanisms and the presser-foot actuating mechanism for automatically unlocking and raising the presser-foot from the work when the machine comes to rest include a lever 296, best shown in Fig. 23, loosely mounted on the stud 242 and provided with a set screw 298 arranged to engage a horizontal arm of the lever 240, a link 300 pivotally connected at its lower end with the lever 296 and at its upper end with an arm 302 (see Figs. 8 and 9) secured to a shaft 304 rotatable at the rear of the machine frame and a second upstanding arm 305 on the shaft acted upon by a set screw 306 carried by the lever 174 of the stopping mechanism. To hold the arm 305 against the set screw 306, a coil spring 307 is stretched between the arm 305 and the machine frame. When the machine is running, the parts are in the position shown in Figs. 9 and 27. Before the machine comes to rest, the cam 168 moves the follower 169 and its connections to force the set screw 306 against the lever 305, rocking the lever 296 in a direction to raise the set screw 298 against the arm of the lever 240 (Figs. 8 and 28). Just before the set screw 298 engages the lever 240, a flat surface on the arm of the lever 296, which carries the set screw 298, engages a roll 308 on an elbow lever 310 pinned

to a shaft 311 rotatable in the machine frame and provided with an arm 312 carrying a set screw 313 which presses the end of link 276 of the presser-foot lock actuating mechanism. To permit the link 276 to move while the lock actuating cam lever 278 to which it is connected remains stationary, the rearward end of the link is drilled to receive a spring 314 compressed between a cap screw 316 at the end of the link and a pin 318 passing through slots in the link and forming the pivotal connection between the link and the cam lever 278. Further movement of the lever 296 causes the presser-foot to be raised from the work and the elbow lever 310 to be latched in lock releasing position by a notched latch arm 320 loosely mounted on the shaft 280 engaging a pawl 322 on the elbow lever. When the machine is started, the follower 169 drops off the cam 168, raising the link 300 and bringing a pin 324 adjustably clamped in a slot in the link against the notched arm 320 to release the elbow lever 310 before the lever 296 is actuated to move the set screw 298 away from the lever 240, thus permitting the presser-foot to clamp the work before the presser-foot mechanism is locked. To hold the elbow lever 310 from following the movements of the lever 296 as the machine is started, the upper arm 312 engages a hooked finger 326 carried by the frame of the machine. To prevent the presser-foot from being raised beyond a predetermined position during the final movements of the machine, the link 236 has adjustably mounted on it a stop plate 330 arranged to engage the head of a bolt 332 (Fig. 8) on the block 253. When the plate 330 engages the bolt 332, further movement of the lever 240 during stopping serves to compress a spring 334 mounted within a passage in the link 236. During normal operation of the machine, the spring 334 presses a pin 238, passing through slots in the link 236 and forming the pivotal connection between the link and the lever 240, against a set screw 338 in the end of the link, the spring 334 being of sufficient strength to raise the presser-foot.

To unlock and raise the presser-foot manually, there is pivotally mounted on the pin 228 a manually operable handle lever 340 (see Figs. 9 and 23) having a rearwardly extending bar 342 secured thereto extending towards a roll 344 carried by an arm of the presser-foot unlocking lever 272. When the handle lever is pushed rearwardly, the bar 342 unlocks the presser-foot actuating mechanism and a lateral extension of the handle lever 340 engages a roll 346 carried by the presser-foot lever 190 to raise the presser-foot from the work. One advantage of this construction is that with the screw 268 loosened to permit the presser-foot to remain yieldingly in engagement with the work, it is possible to raise the presser-foot by direct action on the presser-foot lever rather than requiring an idle movement to take up the looseness between the presser-foot lever and actuating arm 222. To assist the operator in raising the presser-foot manually, the upper end of the handle lever 340 is connected by a rearwardly extending link 348 with one arm of a bell-crank lever 350 rotatable loosely on the shaft 304. The other arm of the lever 350 is connected with a treadle actuated rod 352 so that a greater force may conveniently be exerted in lifting the presser-foot.

Referring more particularly to Figs. 30 and 31, the pull-off device of the present machine may be arranged to be adjusted automatically in a

manner similar to that in prior machines so that the amount of thread measured will be increased or decreased by the same amount as the thickness of the work increases or decreases. When the pull-off device is adjusted in this way, the position of the inter-engaging portions of needle thread 354 and locking thread 356 in completed stitches will be located along a dotted line 357 (Fig. 30) at a uniform distance from the tread surface of the sole, indicated at 358, regardless of the thickness of the sole. Such adjustment gives a desirable result when operating upon heavy soles, but when light work is encountered, the thickness of stock in a sole may be equal to or even less than the thickness of the welt or other part to which the sole is attached. In such cases, if the position of the inter-engaging portions of needle and locking threads is kept at a uniform distance from the uppermost surface of the work, which is contacted by the presser-foot, the inter-engaging portions of threads with thin work may enter the joint between the welt, indicated at 360, and the sole, as at the left end of Fig. 30. Stitches formed in this way are not durable or acceptable with present day stitching practices. To avoid this difficulty, it is preferable when operating on thin work to so adjust the pull-off device that the locking thread will be drawn by the needle thread to a point just below or at the uppermost surface of the work as at the left-hand end of Fig. 31. However, in prior machines, the operation of the pull-off device in this way requires a manual adjustment different from that in which the inter-engaging portions of thread are drawn a substantial distance beneath the uppermost surface of the work as at the right hand end of Fig. 30. With the present machine, means is provided whereby adjustment of the position of inter-engaging portions of needle and locking threads may be made automatically closer to the uppermost surface of thin work than with thick work, so that a seam may be sewn in a sole of progressively increasing thickness and in a welt of uniform thickness beginning with the locking thread 356 entirely located on the uppermost surface of the work and ending at the thickest part with the locking thread a substantial distance beneath said surface of the work, as illustrated by the dotted line 361, Fig. 31, without danger of drawing the inter-engaging portions into the joint between the welt and the sole.

The means for adjusting the pull-off device in the illustrated machine comprises the link 116 and one arm of the lever 240 having an arcuate slot 362, the center of curvature of which, when the presser-foot is in its lowermost position, substantially coincides with a pivot pin 364 forming the connection between the arm 114 connected with the measuring arm 92 and the link 116. The rearward end of link 116 has passing loosely through it a bolt 366, the head of which fits within the slot 362 and is arranged to be clamped at any position along the slot. When clamped at the upper end of the slot, as in Fig. 23, the pull-off device acts to provide an amount of thread for each stitch varying directly with the thickness of the work so that a seam similar to that illustrated in Fig. 30 will be sewn. When the bolt 366 is adjusted to positions lower in the slot 362, the inter-engaging portions of needle and locking threads will be located correspondingly closer to the uppermost surface of thin work than with thick work until when the bolt 366 is

adjusted to its lowermost position where it is substantially in line with the stud 242 about which the lever 240 is fulcrumed, a uniform amount of needle thread will be pulled off, regardless of the thickness of the work, as indicated by the dotted line 367, there being no automatic variation in the amount of needle thread measured.

To prevent escape of the needle thread from control of the take-up roll 24, the arm 20 of the take-up rotates between a stationary shield 368 and a cover plate 370 (Figs. 2, 3, 10 and 12) hingedly mounted on pins 372 secured at the lower end of the cover plate and rotatable in suitable bearings in the frame of the machine. The opposing surfaces of the shield 368 and plate 370 are normal to the axis of rotation of the take-up arm 20, the take-up arm being positioned close to the shield. The inner surface of the cover plate is formed with a circular enlargements 374 projecting towards the shield 368, and concentric with the roll 24 there is mounted on the take-up arm 20 a button 376 (see Fig. 4) engaging the surface of the plate 370. The button 376 is pressed yieldingly against the plate 370 by a spring 378 surrounding a headed screw 380 passing through the center of the button 376. To prevent the spring 378 from affecting free rotation of the roll 24, the roll is rotatable on a hollow stud 382 secured in the take-up arm 20 and the spring 378 acts between the button 376 and the bottom of a central recess in the stud 382. When the cover plate 370 is moved about its hinge pins 372 away from the shield 368, the take-up is rendered accessible for convenient threading or inspection, and when the cover plate is moved towards the shield, its acts with the shield to confine the thread between the two. The hinge for the cover plate is so arranged that when the plate is in contact with the button 376 on the take-up arm, the weight of the plate tends to hold it in place against the yielding pressure of the button. The cover plate is heated by an electric heater 383 inserted in a lug of the cover plate, heat being transferred through the button 376 to the take-up roll 24. The heater is connected to the current supply by any suitable arrangement of wires, as for instance a flexible cable (not shown).

For locking the cover plate in operative position the frame of the machine adjacent the upper end of the plate has a pivotally mounted guard 384, shown more clearly in Fig. 10, provided with a downwardly projecting arm 386 which, when the guard is rotated about its pivot 388 moves along the outer surface of the plate. When the guard is swung forwardly (Fig. 12) the arm moves away from the cover plate so that it may be swung to expose the take-up. The upper end of the guard 384 projects in front of the looper 10 and its actuating mechanism so as to shield the looper as well as other adjacent thread handling devices from accidental contact while the machine is running. When the guard is swung forwardly to unlock the take-up cover plate, the looper and other thread handling devices are exposed for convenient manipulation or threading.

Connections for rotating the take-up (see Figs. 1 to 6 inclusive, and 13 to 16 inclusive) include a variable speed drive between the take-up supporting shaft 22 and a drive shaft 390 mounted parallel to, but with its axis offset from the axis of the shaft 22. The variable speed drive, as illustrated in Figs. 9 and 15, is provided by a drag

link 392 connected between crank arms 394 and 396 respectively on the shafts 390 and 22, the shaft 390 being driven at the same speed of rotation as the sewing shaft 104. Between the sewing shaft 104 and the takeup drive shaft 390 is a train (see Fig. 13) of driving gears 398, 400 and 402 having helical cut teeth. The intermediate gear 400 acts as an idler having bearings in a housing 404 enclosing all of said gears. To regulate the mesh between the idler 400 and the gears 398 and 402, the housing is adjustable in two directions. To regulate the mesh between the gear 402 and the idler 400, the housing is mounted on an eccentric bushing 406 rotatably supported on a cylindrical portion of the frame which forms a bearing for the take-up drive shaft 390, the outer surface of the cylindrical frame portion being concentric with the axis of the shaft. The bushing 406 is provided with a radial flange having arcuate slots 408 through which a pair of bolts 410 pass for securing the housing to the frame of the machine. When the bolts 410 are loosened, the bushing 406 may be rotated to cause the housing 404 to be raised or lowered, thus changing the distance between the centers of the drive shaft 390 and of the bearings for the idler 400. To regulate the mesh between the gear 398 and the idler 400, the housing 404 is arranged to swing about the bushing 406 as a center, and to this end the shafts 280 and 290 project sufficiently to the right of the machine to be received in enlarged openings in lugs 412 (see Fig. 1) extending from the housing 404 and to be engaged by set screws 414 threaded in said lugs. By loosening one of the set screws 414 and tightening the other, the housing 404 is shifted with the idler 400 towards or from the gear 398. To permit adjustment in timing of the take-up, the gear 402 is not connected directly to the take-up drive shaft 390 but the shaft has keyed to it a disk 416 (see Figs. 13 and 16) having slots 418 to receive bolts 420 threaded into the gear 402. By this construction, the relative angular relations of the disk and gear 402 may be changed.

As a result of the variable speed drive between the take-up drive shaft 390 and the take-up shaft 22, when the machine is operating at high speeds, there is a tendency for variations in angular movement of the take-up arm to cause a reaction through the train of driving gears on the sewing shaft 104. In order to prevent or absorb any reaction caused by the variable speed drive on the sewing shaft 104, the gear 398 is yieldingly connected to the sewing shaft 104 in a manner illustrated in Figs. 6 and 13. The yielding connection between the shaft 104 and the gear 398 includes a hub 422 keyed to the shaft 104 and formed with a circular recess at one end carrying a spring 424 compressed between the bottom of the recess and the gear 398. The gear 398 is provided with an inner bearing surface fitting outside the hub 422 and is caused to rotate with the hub by a series of shouldered screws 426 threaded in the hub 422 passing loosely through slots 428 in the gear 398. The slots 428 are parallel to the axis of the shaft 104 and as force is applied through the shaft 104 to rotate gear 398, the angular relation of the teeth on gears 398 and 400 tends to move the gear 398 lengthwise of the shaft, but the spring 424 acts in the reverse direction with sufficient force to resist such movement except from reaction of the variable speed drive at high speeds.

To support and actuate the looper through an arc of relatively short radius close to the needle

in laying the thread in the barb of the needle and then to one side of the needle position where the thread may conveniently be engaged with the thread finger without crowding or otherwise rendering it difficult to design the mechanisms for actuating others of the thread handling devices, the looper is secured in a link 430 forming one member of a four-bar linkage including the frame of the machine (see Figs. 37, 38 and 39). The link 430 is pivotally connected at one end to the arm of a lever 432 pivoted to the frame at 434 and connected to a cam actuated lever 436 through a link 438. The other member of the four-bar linkage consists of an arm 439 rotatable about a pivot 440 on the frame and pivotally connected with the link 430 by a circular shank portion of the looper 10 which passes loosely through the end of arm 439. From the point of pivotal connection between the arm 439 and link 430, the looper 10 is bent forwardly and terminates in a thread carrying eye 442 spaced from the points of pivotal connection between the link 430 and the arms 439 and 432 at one side of a line connecting said pivotal points by a distance greater than the distance between said pivotal points, thereby causing the angular motion of the link 430 to move the thread eye more rapidly than and in the opposite direction to the movement of the link as a whole. The arm of lever 432 connected with the link 430 is shorter than the arm 439 so that when the thread eye 442 carries the thread into the path of the thread finger the pivotal points of connection between the link and the arms will come into alignment with the axis of the pivot 434. When the looper reaches the other extreme position in threading the needle (Fig. 38) the line connecting the pivotal points between the link and the arms is substantially parallel to the line connecting the pivots 434 and 440. With this arrangement, the movement of the looper supporting and actuating mechanism, as it carries the thread about the needle, causes the thread eye to move along a curve having a relatively short radius and as it moves towards the thread finger along a curve of greater radius, the entire path being indicated by the dot-dash line 443 of Fig. 39.

To operate the thread lifter and loop spreader 14 with a rapid movement through a path extending closer or more nearly at right angles to the work than in the machine of the Patent No. 1,169,909, the supporting and actuating mechanism for the lifter is also in the form of a four-bar linkage having one member formed by the frame of the machine, as best shown in Figs. 40 and 41. The thread lifter has a cylindrical shank bent at an angle to the main body of the lifter and clamped within a socket at one end of a link 444. The link 444 enters the space between forked ends on one arm of a lever 446 through which link the shank of the thread lifter passes to form a pivotal connection between the link and lever. The other end of the link 444 is pivotally connected by means of a pin 448 with an arm 450 rotatable on a stud 452 secured in the frame of the machine. The lever 446 is rotatable on the shaft 290 and carries a roll 456 actuated by a cam 458 on the sewing shaft 106. The thread engaging end 459 of the thread lifter 14 extends from its connection with the link 444 at one side of a line connecting the pivotal points of the link and arms 446 and 450, said arms being crossed to cause the angular motion of the link to move the lifter in the direction of movement of the link as a whole. By this arrangement, a

5 relatively short motion imparted to the cam roll 456 will cause a rapid motion to be imparted to the lifter so that in forming the cam slot for the cam roll 456 no abrupt angular portions are necessary.

The awl and needle in the present machine operate in the same fixed plane, the needle entering the work closely as the awl withdraws. The mechanisms for oscillating the needle, awl and 10 needle guide are similar to those in Patent No. 1,169,909. Referring to Figs. 17 to 20 inclusive, the needle 2 is mounted in a carrier or segment 460 rotatably supported on one arm of the bracket 288. The needle guide 3 is mounted for oscillation loosely on the hub of the needle segment 460. The awl 4 is mounted in an awl carrier or segment 462 formed integrally with a pin 464 supported for rotation in both arms of the bracket 288, the needle carrier surrounding a bearing on 15 the bracket and the pin being supported inside the bearing. As in the machine of Patent No. 1,169,909 the driver 466 for the awl is made in two parts, one part of which is journaled on a second arm of the bracket 288 and the other part 20 of which projects beyond the awl segment and has a collar portion surrounding the pin 464. Between the two parts the hub of the awl driver is cut away to cooperate with a similarly cut away portion of the awl segment so that the pin 464 25 and the needle segment may be adjusted lengthwise without moving the awl driver 466.

To enable the alignment of the needle and awl to be adjusted in the present machine and to cause them to operate in the same plane 30 without looseness between the parts as a result of wear, the awl supporting pin 464 is engaged at opposite ends by screws 468 and 470. The set screw 470 is threaded in the arm of the bracket 288 which supports the awl driver 466 and the screw 468 is threaded in a sleeve 472 in the other arm of the bracket 288 forming a bearing for the pin 464 at one end and fitting inside the collar portion of the awl driver 466 at the other end. The sleeve 472 has a shoulder 473 which engages 35 a radial surface formed at the end of an enlarged opening in the hub of the needle segment 460 so that as the set screw 468 is turned into the sleeve 472 it draws the shoulder of the sleeve against the needle segment, shifting the pin 464 axially and adjusting the relative positions of the needle and awl. After the set screw 468 has been 40 adjusted to bring the needle and awl into the same plane, the set screw 470 acting on the other end of the pin 464 may be adjusted to take up looseness between the parts. To prevent rotation of the sleeve 472 the shoulder of the sleeve has a flat sided enlargement 474 which fits within a correspondingly shaped recess formed in a tubular portion of the needle supporting bracket 45 arm.

To guide the work through the machine there is pivotally mounted on the awl driver supporting arm of bracket 288, an edge gage in the form of a lever 476, the position of which may be adjusted towards or from the seam line by a radial cam 478 engaging a rearwardly extending arm of the lever. These parts are illustrated in Figs. 3, 8 and 16. The pivot 480 for the lever passes 50 through an angularly bent ear formed on the lever, through a lug formed on the bracket 288 and into the central part of the lever, as more clearly illustrated in Fig. 8, and the work guiding arm of the lever is curved upwardly and 55 formed with a rounded work engaging surface

482. The adjusting cam 478 is secured to the upper end of a vertical shaft 484 rotatable in the frame of the machine, and the lower end of the shaft has a pinion 486 (Fig. 3), the teeth of which mesh with gear teeth on a segmental arm 488 fast on a vertical shaft 490. The shaft 490 extends downwardly through a bearing in the machine frame and at its lower end has secured to it a stop arm 492 (Fig. 5) provided with a set screw 494 arranged to engage a portion of the machine frame for limiting the rotation of the shaft 490, and the movement of the edge gage towards the seam line.

The illustrated machine is also provided with a channelling knife for cutting a groove in the surface of the welt to receive the stitches of the seam, and with improved means for actuating the knife 496 towards and from operative position. The knife 496 projects through the sewing slot of the work support at its upper end and at its lower end is secured in a chuck 498 carried by a vertical slide 500. The slide 500 is held in a guideway 502 and at its lower end has a cam roll 504 entering a slot in a cam 506 on the segmental arm 488. The cam 506 is mounted on the arm 488 in concentric relation to the segmental portion, but separated radially from the gear teeth a sufficient distance to permit the pinion 486 to enter the space between the cam and the gear teeth. Construction of the arm in this manner provides a rigid arrangement for simultaneously adjusting the positions of the edge gage and channelling knife.

To enable the edge gage and channelling knife adjustments to be made together with a change in length of feed, the feed control hand lever 214 is fulcrumed on a stud screw 508 passing loosely through the central part of an arm 510 arranged to swing with the hand lever about a fixed pivot 512 (see Fig. 3). When the hand lever is actuated, it first rotates about its fulcrum on the arm 510, and thereafter swings with the arm about the pivot 512 for the arm, thus the hand lever is actuatable about either of two centers and is connected to the pivot 213 of the feed length changing link 212 close to the fulcrum screw 508, so that movement of the lever with the arm 510 will cause an adjustment of the feed. The hand lever is also connected to the segmental arm 488 at a point substantially in line with the pivot 512 of the arm 510 so that movement of the lever about its fulcrum will cause the edge gauge and channelling knife to be adjusted. The connection between the hand lever 214 and the arm 488 comprises a pin 514 on the hand lever and a lug on the arm 488 having a slot 516 to receive the pin 514. The free end of the arm 510 slides along a perforated guide block 518 in which are inserted stop pins 520 to limit the movement of the arm 510. To permit a more accurate adjustment in the movement of the arm 510 than that afforded by removing and inserting the pins 520, in the perforations of the block 518, the block 518 is slidably mounted in the machine frame and has its position controlled by a micrometer thumb screw 522. To prevent movement of the arm 510 with the hand lever until after the edge gage and channelling knife have been adjusted, the arm 510 has secured to its under surface a friction plate 524 acting against an arcuate guide 526 on the machine frame. The friction plate 524 is pressed against the guide by a spring 528 coiled about a screw 530 passing loosely through the plate and into a threaded

opening in the hand lever, the plate being perforated to receive a pin 532 fixed in the hand lever to prevent rotation of the plate on the screw. When the handle end of the hand lever 514 is moved rearwardly, the edge gage and channelling knife actuating arm 488 again is adjusted to return the edge gage and channelling knife to inoperative positions after which an adjustable thumb screw 534 passing through the hand lever 10 engages an upstanding lug on the arm 510, forcing the arm rearwardly with the hand lever.

To apply a limited quantity of oil to the needle while the machine is running, an oil saturated wick 536 extending from the forward end of a lever 538, best shown in Figs. 40 and 41, is carried against the needle between the needle guide and the needle segment. The lever 538 is fulcrumed on an adjustable eccentric pin 540 and is provided with an enlargement 542 within which 15 a supply of oil is contained. During operation of the machine the lever 538 is actuated to cause the wick 536 to wipe the needle and to be raised sufficiently to permit passage of the needle segment towards the work. To actuate the lever 538, the rearwardly extending arm of the lever 25 has rotatably mounted on it a block 544 fitting a slot within an arm on the thread finger actuating cam lever 446.

Certain of the mechanisms which have been 30 illustrated and described are not claimed herein but form the subject of divisional applications, the feeding and presser foot actuating mechanism forming the subject-matter of application Serial No. 346,160, filed July 18, 1940, and the 35 rotary take-up, driving mechanism and supporting devices forming the subject-matter of application Serial No. 356,336, filed September 11, 1940.

The nature and scope of the invention having 40 been indicated, and an embodiment of the invention having been specifically described, what is claimed is:

1. A lockstitch sewing machine having, in combination, stitch forming devices including a hook 45 needle, a locking thread case, a rotary loop taker for passing loops of needle thread over the thread case, and a take-up, mechanism for actuating the take-up to provide slack in the needle thread as the needle loop is being drawn through the 50 work by stitch forming devices other than the take-up and to pull each needle loop from the loop taker, and means for controlling the needle thread as each loop is passing over the thread case to prevent slack thread in the needle loop 55 during passage of the loop from a position of maximum extension to a position where it is free of the loop taker.

2. A lockstitch sewing machine having, in combination, stitch forming devices including a hook 60 needle, a locking thread case, a rotary loop taker for passing loops of needle thread over the thread case, and a continuously rotating take-up arranged to provide slack in the needle thread as the needle loop is being drawn through the work by stitch forming devices other than the take-up and to pull each needle loop from the loop taker, and means acting with the take-up to permit each needle loop to be carried about the locking thread case without substantial tension and to prevent slack thread in the needle loop during passage of the loop from a position of maximum extension about the thread case to a position where it is free of the loop taker.

3. A lockstitch sewing machine having, in combination, stitch forming devices including a hook

needle, a locking thread case, a rotary loop taker for passing loops of needle thread over the thread case, and a take-up arranged to provide slack in the needle thread as the needle loop is being drawn through the work by stitch forming devices other than the take-up and to pull each needle loop from the loop taker, and a yielding thread engaging member having a range of movement limited sufficiently to permit the needle loop to be carried about the thread case without substantial tension, but to prevent slack in the needle loop as the loop is passing from a position of maximum extension to a position where it is free of the loop taker.

4. A lockstitch sewing machine having, in combination, stitch forming devices including a hook needle, a locking thread case, a rotary loop taker for passing loops of needle thread over the thread case, and a take-up arranged to provide slack in the needle thread as the needle loop is being drawn through the work by stitch forming devices other than the take-up and to pull each needle loop from the loop taker, a yielding thread engaging member, and means for limiting the range of movement of the thread engaging member to permit the needle loop to be carried about the thread case without substantial tension and to render said member operative to hold the thread yieldingly while the needle loop is passing from a position of maximum extension to a position where it is free of the loop taker.

5. A lockstitch sewing machine having, in combination, stitch forming devices including a hook needle, a locking thread case, a rotary loop taker for passing loops of needle thread over the thread case, and a take-up arranged to provide slack in the needle thread as the needle loop is being drawn through the work by stitch forming devices other than the take-up and to pull each needle loop from the loop taker, and a movably mounted member for holding the needle thread yieldingly with a relatively light force during one part of its movement and with a relatively heavy force during another part of said movement to cause said member to exert a yielding tension on the needle thread during passage of the needle loop from a position of maximum extension to a position where it is free of the loop taker.

6. A lockstitch sewing machine having, in combination, stitch forming devices including a hook needle, a locking thread case, a rotary loop taker for passing loops of needle thread over the thread case, and a take-up arranged to provide slack in the needle thread as the needle loop is being drawn through the work by stitch forming devices other than the take-up and to pull each needle loop from the loop taker, a thread engaging member for holding the needle thread yieldingly with a relatively light force during one part of its movement and with a relatively heavy force during another part of its movement to cause said member to exert a yielding tension on the needle thread during passage of the loop from a position of maximum extension to a position where it is free of the loop taker, and means for limiting the movement of the thread engaging member while taking up thread to permit the needle loop to be carried about the thread case by the loop taker without substantial tension.

7. A lockstitch sewing machine having, in combination, stitch forming devices including a hook needle, a locking thread case, a rotary loop taker for passing loops of needle thread over the thread case, and a take-up arranged to provide slack in the needle thread as the needle loop is being

drawn through the work by stitch forming devices other than the take-up and to pull each needle loop from the loop taker, a thread engaging member for holding the needle thread yieldingly during passage of the loop from a position of maximum extension to a position where it is free of the loop taker, and means for guiding the needle thread to cause the thread engaging member to exert a rapidly increasing tension on the needle thread as the thread held by the thread engaging member is given up.

8. A lockstitch sewing machine having, in combination, stitch forming devices including a hook needle, a locking thread case, a rotary loop taker for passing loops of needle thread over the thread case, and a take-up arranged to provide slack in the needle thread as the needle loop is being drawn through the work by stitch forming devices other than the take-up and to pull each needle loop from the loop taker, a thread engaging member for holding the needle thread yieldingly during passage of the loop from a position of maximum extension to a position where it is free of the loop taker, and guides for the needle thread at either side of the thread engaging member for causing said member to deflect the thread out of a straight path and to permit the thread to approach a substantially straight line between said guides as the tension on the thread increases.

9. A lockstitch sewing machine having, in combination, stitch forming devices including a hook needle, a locking thread case, a rotary loop taker for passing loops of needle thread over the thread case, and a take-up arranged to provide slack in the needle thread as the needle loop is being drawn through the work by stitch forming devices other than the take-up and to pull each needle loop from the loop taker, a thread engaging member for holding the needle thread yieldingly during passage of the loop from a position of maximum extension to a position where it is free of the loop taker, and means for causing the thread engaging member to exert a yielding force on the thread progressively approaching that required to set a stitch as the thread moves the thread engaging member to the limit of its movement.

10. A lockstitch sewing machine having, in combination, stitch forming devices including a hook needle, a locking thread case, a rotary loop taker for passing loops of needle thread over the thread case, and a take-up arranged to provide slack in the needle thread as the needle loop is being drawn through the work by stitch forming devices other than the take-up and to pull each needle loop from the loop taker, thread engaging means for holding back the needle thread and giving up part only of the amount held back as the loop of needle thread is passing from a position of maximum extension over the thread case to a position where the loop is free of the loop taker, and frictional means separate from the work for causing the needle loop to reach a position of maximum extension on the thread case invariably at the same angular position of the loop taker.

11. A lockstitch sewing machine having, in combination, stitch forming devices including a hook needle, a locking thread case, a rotary loop taker for passing loops of needle thread over the thread case, and a take-up arranged to provide slack in the needle thread as the needle loop is being drawn through the work by stitch forming devices other than the take-up and to pull each

needle loop from the loop taker, means for controlling the needle thread to prevent slack in the needle loop as the loop is passing from a position of maximum extension about the thread case to a position where the loop is free of the loop taker, and a frictional tension acting on the needle thread between the take-up and the work to prevent slack thread in the needle loop as the loop taker carries the needle loop about the thread case.

12. A lockstitch sewing machine having, in combination, stitch forming devices including a hook needle, a locking thread case, a rotary loop taker for passing loops of needle thread over the thread case, and a take-up arranged to provide slack in the needle thread as the needle loop is being drawn through the work by stitch forming devices other than the take-up and to pull each needle loop from the loop taker, and yielding means acting with the take-up as each loop is passing over the thread case to prevent slack thread in the needle loop before the loop reaches a position during its passage over the thread case where it is free of the loop taker.

13. A lockstitch sewing machine having, in combination, a work support, a presser foot movable towards and from the work support to clamp the work, stitch forming devices including at the presser foot side of the work, a locking thread case and a loop taker for passing loops of needle thread over the thread case, and at the work support side of the work, a take-up, a needle thread pull-off, and a thread lock between the pull-off and the take-up, and mechanism for actuating the stitch forming devices to cause the thread lock to open before the needle loop is carried by the loop taker to a position of maximum extension about the thread case.

14. A lockstitch sewing machine having, in combination, a work support, a presser foot movable towards and from the work support to clamp the work, stitch forming devices including at the presser-foot side of the work, a locking thread case and a loop taker for passing loops of needle thread over the thread case and at the other side of the work, a take-up, a needle thread pull-off, and a thread lock between the pull-off and the take-up, mechanism for actuating the stitch forming devices to cause the thread lock to open before the needle loop is carried by the loop taker to a position of maximum extension about the thread case, and yielding means for preventing slack thread in the needle loop during passage of the loop over the thread case.

15. A lockstitch sewing machine having, in combination, stitch forming devices including a locking thread case, a loop taker for passing loops of needle thread over the thread case, a take-up, a needle thread pull-off and a thread lock between the pull-off and take-up, a presser-foot and a work support arranged to clamp and feed the work, and mechanism for actuating the stitch-forming devices to cause the thread lock to open before the needle loop is carried by the loop taker over the thread case.

16. A lockstitch sewing machine having, in combination, a work support, a presser foot movable towards and from the work support to clamp the work, stitch forming devices including at the presser-foot side of the work, a locking thread case, and a loop taker for passing loops of needle thread over the thread case and at the work support side of the work, a take-up, a needle thread pull-off, and a thread lock between the pull-off and the take-up, mechanism for actu-

ating the stitch forming devices to cause the thread lock to open and the pull-off to give up a measured supply of thread before the needle loop is carried by the loop taker to a position of greatest extension about the thread case, and a frictional tension device acting on the needle thread between the take-up and the work to maintain a tension on the needle thread along that portion operated on by the thread lock after the needle loop is freed from the loop taker and is being drawn towards the work by the take-up.

17. A lockstitch sewing machine having, in combination, a work support, a presser foot movable towards and from the work support to clamp the work, stitch forming devices including at the presser-foot side of the work a hook needle, a locking thread case, and a loop taker for passing loops of needle thread over the thread case, and at the work support side of the work, a take-up, and a needle thread pull-off device, and connections between the presser-foot and the pull-off device for causing the position of inter-engaging portions of needle and locking threads in completed stitches to be closer to the surface of the work engaged by the presser-foot than with thick work.

18. A lockstitch sewing machine having, in combination, a work support, a presser foot movable towards and from the work support to clamp the work, stitch forming devices including a hook needle, a locking thread case, a loop taker for passing loops of needle thread over the thread case, and a needle thread pull-off device, connections between the presser-foot and the pull-off device for causing the position of inter-engaging portions of needle and locking threads in completed stitches to be closer to the surface of the work engaged by the presser-foot with thin work than with thick work, and means for adjusting said connections to cause the position of inter-engaging portions of needle and locking threads in completed stitches to be spaced from the surface engaged by the presser-foot equally with both thick and thin work.

19. A lockstitch sewing machine having, in combination, a work support, a presser foot movable towards and from the work support to clamp the work, stitch forming devices including a hook needle, a locking thread case, a loop taker for passing loops of needle thread over the thread case, and a needle thread pull-off device, connections between the presser-foot and the pull-off device for causing the position of inter-engaging portions of needle and locking threads in completed stitches to be spaced from the surface engaged by the presser-foot equally with both thick and thin work, and means for changing the ratio of movements imparted to the pull-off device by said connections to cause the inter-engaging portions of needle and locking threads in completed stitches with thin work to be located in a predetermined relation to the surface engaged by the presser-foot, and with thick work to be located automatically at a different relation to the surface of the work engaged by the presser-foot.

20. A lockstitch sewing machine having, in combination, a work support, a presser foot movable towards and from the work support to clamp the work, stitch forming devices including a hook needle, a locking thread case, a loop taker for passing loops of needle thread over the thread case, and a needle thread pull-off device, connections between the presser-foot and the pull-off device for causing the position of inter-engaging portions of needle and locking threads in

completed stitches to change when the thickness of the work changes, manual means for adjusting the pull-off device to cause the inter-engaging portions of needle and locking threads in completed stitches to be located at the same distance from the surface of the work engaged by the presser-foot for all thicknesses of work, or to cause the inter-engaging portions of needle and locking threads to be located automatically at any other distance from the surface of the work engaged by the presser-foot when the thickness of work changes.

21. A lockstitch sewing machine having, in combination, a work support, a presser-foot movable towards and from the work support to clamp the work, stitch forming devices including at one side of the work a hook needle, a locking thread case, and a loop taker for passing loops of needle thread over the thread case and at the other side of the work, a take-up, a needle thread pull-off device, a thread measuring arm for holding the needle thread in the path of the pull-off, and connections between the presser-foot and the measuring arm comprising a curved arm and a link slidable along the arm at one end and provided with a pivoted connection at the other end arranged concentric to the curvature of said arm when the presser-foot is in its lowermost position with no work in the machine.

22. A lockstitch sewing machine having, in combination, a hook needle, a loop taker, a take-up, a thread lock against which each stitch is set comprising a truck for guiding the thread and a shoe movable towards and from the truck, and a cam acting on the shoe radially of the truck to press the shoe against the thread.

23. A lockstitch sewing machine having, in combination, a hook needle, a loop taker, a take-up, a thread lock against which each stitch is set comprising a truck for guiding the thread and a shoe movable towards and from the truck, and a cam having a pivotal mounting at one side of the truck arranged for actuation against the shoe in a direction in which the point of engagement between the cam and the shoe approaches a line connecting the axis of the truck and the pivotal mounting of the cam.

24. A lockstitch sewing machine having, in combination, a hook needle, a loop taker, a take-up, a thread lock against which each stitch is set comprising a truck for guiding the thread and a shoe movable towards and from the truck, a cam acting on the shoe radially of the truck to press the shoe against the thread, and yielding means for actuating the cam against the shoe.

25. A lockstitch sewing machine having, in combination, a hook needle, a loop taker, a take-up, a thread lock against which each stitch is set comprising a truck for guiding the thread and a shoe movable towards and from the truck, a cam acting on the shoe radially of the truck to press the shoe against the thread, yielding means for actuating the cam against the shoe, and means operated during each sewing cycle to actuate the cam away from the shoe.

26. A lockstitch sewing machine having, in combination, a hook needle, a loop taker, a take-up, a thread lock against which each stitch is set comprising a truck for guiding the thread, a shoe co-operating with the truck to grip the thread passing over the truck and having an external arcuate surface concentric with the axis of the truck when gripping the thread, and means engaging the arcuate surface of the shoe to press the shoe against the thread.

27. A lockstitch shoe sewing machine having, in combination, a hook needle, a loop taker, a take-up, a pair of thread guiding trucks, a needle thread pull-off acting on the thread between the trucks, a shaft on which the pull-off is mounted for oscillation to pull off thread, shoes engaging the thread passing over the trucks to lock the thread, and arms supported by the shaft for pressing the shoes against the said trucks.

28. A lockstitch shoe sewing machine having, in combination, a hook needle, a loop taker, a take-up, a pair of thread guiding trucks, a needle thread pull-off acting on the thread between the trucks, a shaft on which the pull-off is mounted for oscillation to pull off thread, shoes engaging the thread passing over the trucks to lock the thread, arms supported by the shaft for pressing the shoes against the said trucks, and mechanism for holding both arms against the shoes at certain times in each sewing cycle and for actuating the pull-off after one arm is moved away from its respective shoe and the other arm remains in locking engagement with the other shoe.

29. A lockstitch shoe sewing machine having, in combination, a hook needle, a loop taker, a take-up, a pair of thread guiding trucks, a needle thread pull-off acting on the thread between the trucks, a first shaft on which the pull-off is mounted for oscillation to pull off thread, shoes engaging the thread passing over the trucks to lock the thread, arms supported by the first shaft for forcing the shoes against said trucks, a second shaft aligned with the first shaft, a fixed measuring arm mounted on said second shaft for holding the thread in position to be operated on by the pull-off, and mechanisms for actuating the measuring arm as the work operated upon changes in thickness for holding both arms against the shoes at certain times in each cycle and for actuating the arms alternately away from their respective shoes while the pull-off acts.

30. A lockstitch shoe sewing machine having, in combination, a hook needle, a loop taker, a take-up, a needle thread pull-off, thread locks between which the pull-off acts comprising trucks for guiding the thread, shoes for gripping the thread against the trucks, cams for forcing the shoes against the thread, and a single shaft on which said pull-off and cams are supported for oscillation concentrically about the same axis.

31. A lockstitch sewing machine having, in combination, a main sewing shaft, stitch forming devices operated from the sewing shaft including a needle, a loop taker, a take-up, a pull-off, a front thread lock between the take-up and the pull-off and a rear thread lock between the pull-off and the supply, means for actuating the stitch forming devices during sewing to cause the take-up to set the stitch while the rear thread lock is closed and to close the front thread lock while the thread is being strained by the take-up, and means for actuating both thread locks at the completion of sewing to cause the locking thread held in the bight of the last needle loop to remain outside the surface of the work.

32. A lockstitch sewing machine having, in combination, a main sewing shaft, stitch forming devices operated from the sewing shaft including a needle, a loop taker, a take-up, a pull-off, a front thread lock between the take-up and the pull-off and a rear thread lock between the pull-off and the supply, means for actuating the stitch forming devices during sewing to cause the

take-up to set the stitch while the rear thread lock is closed and to close the front thread lock while the thread is being strained by the take-up, driving and stopping mechanisms for bringing the machine to rest with the take-up close to its stitch setting position, and means controlled by the driving and stopping mechanisms for actuating both thread locks at the completion of sewing to cause the locking thread held by the bight of the last needle loop to remain outside the surface of the work.

33. A lockstitch sewing machine having, in combination, a main sewing shaft, stitch forming devices operated from the sewing shaft including a needle, a loop taker, a take-up, a pull-off, a front thread lock between the take-up and the pull-off and a rear thread lock between the pull-off and the supply, means for actuating the stitch forming devices during sewing to cause the take-up to set the stitch while the rear thread lock is closed and to close the front thread lock while the thread is being strained by the take-up, driving and stopping mechanisms for bringing the machine to rest with the take-up close to its stitch-setting position, and means controlled by the driving and stopping mechanisms for actuating both thread locks while the machine is being brought to rest to release the thread before the take-up reaches a stitch-setting position.

34. A lockstitch sewing machine having, in combination, a main sewing shaft, driving and stopping mechanisms therefor, stitch forming devices including a needle, a shuttle, a take-up, a pull-off, a front thread lock between the take-up and pull-off and a rear thread lock between the pull-off and the supply, cams on the sewing shaft, cam levers actuated by the cams, thread lock operating rods, springs connecting the rods and the levers arranged to close the locks, and means controlled by the driving and stopping mechanisms for actuating the rods simultaneously against the forces of the springs to open both locks when the machine is brought to rest.

35. A shoe sewing machine having, in combination, a main frame, a sewing shaft in the frame, a curved hook needle, and mechanism driven from the sewing shaft for laying the thread in the hook of the needle comprising a four-bar linkage including the frame, a pair of arms pivoted to the frame, a looper, and a link to which the looper is attached pivotally connected at each end to one of said pair of arms.

36. A shoe sewing machine having, in combination, a main frame, a sewing shaft in the frame, a curved hook needle, and mechanism for threading the needle comprising a four-bar linkage including the frame, a pair of arms pivoted to the frame, a link pivotally connected at each end to one of said pair of arms, and a looper attached to the link and formed with a thread carrying eye spaced from the points of pivotal connection between the link and the arms at one side of a line connecting said pivotal points.

37. A shoe sewing machine having, in combination, a main frame, a sewing shaft in the frame, a curved hook needle, a thread finger, and mechanism for threading the needle comprising a four-bar linkage including the frame, a pair of arms pivoted to the frame, a link pivotally connected at each end to one of said pair of arms, and a looper attached to the link and formed with a thread carrying eye spaced from the points of pivotal connection between the link and the arms at one side of a line connecting said pivotal points to cause the thread carrying eye to

move across and outside the plane of the needle, one of said pair of arms being shorter than the other to cause the thread eye to move along a curve of greater radius at one side of the needle plane than at the other.

38. A shoe sewing machine having, in combination, a main frame, a sewing shaft in the frame, a curved hook needle and mechanism for threading the needle comprising a four-bar linkage including the frame, a pair of arms pivoted to the frame and a link pivotally connected at each end to one of said pair of arms, and a looper attached to the link and formed with a thread carrying eye spaced from the points of pivotal connection between the link and the arms at one side of a line connecting said pivotal points, the thread eye of the looper being a greater distance from either of said pivotal points than said pivotal points are spaced apart to cause the angular motion of said link to move the thread eye more rapidly than the movement of the link as a whole while threading the needle.

39. A shoe sewing machine having, in combination, a main frame, a sewing shaft in the frame, a curved hook needle, a thread finger, and mechanism for threading the needle comprising a four-bar linkage including the frame, a pair of arms pivoted to the frame, a link pivotally connected at each end to one of said pair of arms, a looper attached to the link and formed with a thread carrying eye spaced from the points of pivotal connection between the link and the arms at one side of a line connecting said pivotal points to cause the thread carrying eye to move across and outside the plane of the needle, one of said pair of arms being shorter than the other to cause the thread eye to move along a curve of greater radius at one side of the needle plane than at the other, and means driven from the sewing shaft for actuating the shorter of said pair of arms.

40. A shoe sewing machine having, in combination, a main frame, a sewing shaft in the frame, a curved hook needle, and mechanism for threading the needle comprising a four-bar linkage including the frame, a pair of arms pivoted to the frame, a link pivotally connected at each end to one of said pair of arms, and a looper attached to the link and formed with a thread carrying eye spaced from the points of pivotal connection between the link and the arms at one side of a line connecting said pivotal points, the thread eye of the looper being a greater distance from either of said pivotal points than said pivotal points are spaced apart to cause the angular motion of said link to move the thread eye in a direction reverse from the movement of the link as a whole while threading the needle.

41. A shoe sewing machine having, in combination, a main frame, a sewing shaft in the frame, a curved hook needle, and mechanism for threading the needle comprising a four-bar linkage including the frame, a pair of arms pivoted to the frame, a link pivotally connected at each end to one of said pair of arms, and a looper attached to the link and formed with a thread carrying eye spaced from the points of pivotal connection between the link and the arms at that side of a line connecting said points opposite to the pivots for said arms on the frame.

42. A lockstitch shoe sewing machine having, in combination, a main frame, a sewing shaft in the frame, a curved hook needle, a loop taker, means for spreading the loop of thread carried by the needle and presenting it to the loop taker

comprising a four-bar linkage including the frame, a pair of arms pivoted to the frame, a link pivotally connected between said arms, and a loop lifter attached to the link at one side of a line connecting the pivotal points of the link and arms. 5

43. A lockstitch shoe sewing machine having, in combination, a main frame, a sewing shaft in the frame, a curved hook needle, a loop taker, means for spreading the loop of thread carried by the needle and presenting it to the loop taker comprising a four-bar linkage including the frame, a pair of arms pivoted to the frame, a link pivotally connected between said arms, and a loop lifter attached to the link at that side of a line 15 connecting the pivotal points of the link and arms opposite to the pivots for said arms on the frame, said arms being crossed to cause the angular motion of the link to move the lifter in the direction of movement of said link as a whole. 10

44. A sewing machine having, in combination, stitch forming devices including a curved hook needle, a curved awl, an awl carrier, a pivot pin for the awl rigid therewith, means for oscillating the awl carrier, a fixed bracket having 25 arms at opposite sides of the awl carrier for supporting the pin, a needle carrier surrounding the pin adjacent one arm of the bracket, an awl driver surrounding the pin adjacent the other arm of the bracket, and means acting on the 30 ends of said pin for adjusting the pin lengthwise to locate the awl permanently in the plane of the needle.

45. A sewing machine having, in combination, stitch forming devices including a curved hook 35 needle, a curved awl, an awl carrier, a pivot pin for the awl rigid therewith, means for oscillating the awl carrier, a fixed bracket having arms at opposite sides of the awl carrier for supporting the pin, a needle carrier surrounding the pin adjacent one arm of the bracket, an awl driver surrounding the pin adjacent the other arm of the bracket, a shouldered sleeve in the bracket between the pin and the needle carrier arranged to hold the needle carrier against the adjacent bracket, an adjustable set screw in the sleeve acting on one end of the pin to secure the awl against movement relatively to the needle in one direction axially of the pin, and an adjustable set screw in the bracket adjacent the awl carrier to secure the awl against movement relatively to the needle in the other direction axially of the pin. 40

46. A shoe sewing machine having, in combination, stitch forming and work feeding devices, an edge gage past which the work is fed, a work channelling knife operating while in engagement with the work to cut the work in the line of feed, and means for moving the edge gage towards and from the line of feed and for moving the knife 55 towards and from engagement with the work including a manually operable member, a pivotally mounted arm connected to the manually operable member having concentric gear segment and cam portions, a pinion meshing with teeth of the gear segment portion for adjusting the position of the edge gage, and a follower engaging the cam portion 60 for moving the knife. 65

47. A shoe sewing machine having, in combination, stitch forming and work feeding devices, an edge gage past which the work is fed, a work 70

channelling knife operating while in engagement with the work to cut the work in the line of feed, and means for moving the edge gage towards and from the line of feed and for moving the knife towards and from engagement with the work including a manually operable member, a pivotally mounted arm connected to the manually operable member having concentric gear segment and cam portions, a pinion between the cam and gear portions meshing with the teeth of the gear portion for adjusting the position of the edge gage, and a follower engaging the cam portion of the arm at the opposite side from the gear portion for moving the knife. 5

48. A shoe sewing machine having, in combination, stitch forming and work feeding devices, an edge gage past which the work is fed, a work channelling knife operating while in engagement with the work to cut a stitch receiving groove in the work, and means for moving the edge gage towards and from the line of the seam and the knife towards and from engagement with the work and for changing the length of feed including a manually operable lever arranged to be actuated about two centers, actuation about one of which causes movement of the edge gage and channelling knife towards or from operative positions and actuation about the other of which causes change in the length of feed. 10

49. A shoe sewing machine having, in combination, stitch forming and work feeding devices, an edge gage past which the work is fed, a work channelling knife operating while in engagement with the work to cut a stitch receiving groove in the work, means for moving the edge gage towards and from the line of the seam and the knife towards and from engagement with the work and for changing the length of feed including a manually operable lever arranged to be actuated about two centers, actuation about one of which causes movement of the edge gage, and channelling knife towards or from operative positions and actuation about the other of which causes change in the length of feed, and friction means for causing the lever to be actuated about one center before being actuated about the other. 30

50. A shoe sewing machine having, in combination, stitch forming and work feeding devices, an edge gage past which the work is fed, a work channelling knife operating while in engagement with the work to cut a stitch receiving groove in the work, means for moving the edge gage toward and from the line of the seam and the knife towards and from engagement with the work and for changing the length of feed including a manually operable lever arranged to be actuated about two centers, actuation about one of which causes movement of the edge gage and channelling knife towards or from operative positions and actuation about the other of which causes change in the length of feed, an arm connected to the manually operable member having concentric gear and segment portions, a pinion meshing with teeth on the gear segment portion for adjusting the position of the edge gage, a follower engaging the cam portion for moving the knife, and an adjustable stop for said arm to limit the movements of the edge gage and channelling knife towards operative positions. 55
